UNITED STATES PATENT OFFICE.

JOHN A. BERRYMAN, OF NEW YORK, N. Y.

STOVE ATTACHMENT.

1,244,690.

Specification of Letters Patent. Patented Oct. 30, 1917.

Application filed December 12, 1916. Serial No. 136,463.

To all whom it may concern:

Be it known that I, JOHN A. BERRYMAN, a citizen of the United States, residing at New York, in the county and State of New York, have invented a new and useful Improvement in Stove Attachments, of which the following is a specification.

This invention relates to attachments for stoves, and has for its object to provide for utilizing as far as possible all the heat generated from a stove burner.

It is the special aim of the invention to provide an improved cover for gas or other stoves which enables the heat generated by a single burner to be utilized for heating two cooking vessels or other articles and furnishing hot water for domestic use, whereby it is possible to perform with one burner the same service and attain the same results as are now ordinarily obtained by the combined use of two burners of a gas stove and one burner of a gas water heater. Another object is to as evenly as possible distribute the heat units generated from the single burner between the two cooking vessels or other articles to be heated.

The invention will be first hereinafter described in connection with the accompanying drawings, which constitute part of this specification, and then more specifically defined in the claims at the end of the description.

In the accompanying drawings, wherein similar reference characters are used to designate corresponding parts throughout the several views:

Figure 1 is a plan view of an attachment or cover for gas stoves made substantially in accordance with this invention.

Fig. 2 is a plan view of the attachment with the top plate removed.

Fig. 3 is a detailed longitudinal section of one of the steam generating and ejecting devices used for effecting an even distribution of the heat units from a single burner between two openings in the top of the attachment.

Fig. 4 is a section on the line IV—IV of Fig. 2.

Fig. 5 is a section on the line V—V of Fig. 2, and

Fig. 6 is a side view of the attachment.

The attachment comprises a flue box having a top plate 1, a bottom plate 2 spaced below the same, and inclosing walls 3 extending between the top and bottom plates all

the way around the latter. The top plate is provided with one opening 4 arranged in vertical alinement with the burner of a gas stove (not shown), and another opening 5 arranged out of line with said burner. The bottom plate has an opening 6 in vertical alinement with each of the openings 4 in the top plate, but has no openings corresponding to the openings 5 in said top plate. It will be understood that the attachment is placed on top of an ordinary gas stove so that the openings 6 will be directly over and above two of the burners (not shown). Inclined plates 7 extend from adjacent the margins of the openings in the bottom plate to the farther margins of the openings 5 in the top plate, and serve to direct some of the heat units to the openings 5. A vertical partition 8 divides the inclosure in the attachment into two compartments, each including one each of the openings 4, 5 and 6 and one of the inclined plates 7. The provision of this partition makes it possible to use one burner only without allowing any of the heat units to be distributed to more than one of the openings 4 and one of the openings 5.

The top plate is chambered as at 9, around the openings 4 and 5 and through said chambered portion water is circulated for the purpose of heating the same. A coil or pipe 10 may also be arranged over one or more of the openings 6 in the bottom plate 2 so as to be directly in the flame from the burner. Cold water from a boiler or tank (not shown) is supplied to the coil 10 and the chambered portion of the top plate by a pipe 11, Figs. 2 and 6, a branch pipe 12, Fig. 5, leading from the pipe 11 to the coil, and another branch pipe 15 leading from said pipe 11 to the chamber 9. After circulating through said coil and chamber, the hot water returns to the boiler or tank through branch pipes 13 and 16 leading respectively from the chamber 9 and the coil 10, and a pipe 14 connected to said branch pipes, Figs. 2, 4 and 6.

To insure the proper distribution of the heat units between each pair of openings 4 and 5 in the top plate, a steam generator and ejector 18, is placed above each of the openings 6 in the bottom plate so as to be directly in the flame. As illustrated in Fig. 3, each of the steam generators and ejectors 18 comprises a long tubular body to which water is fed from the pipe 11 via a branch

pipe 17, Figs. 2 and 6, and a small tube 21 connected to a partition 22 in the outer end of the body. The flow of the water to the body of the generator, which is directly in 5 the flame, is controlled by a needle valve 19 having its tapered end 24 coöperating with a funnel-shaped opening 23 in said partition 22. The inner end of the body of the generator is conical and provided with a 10 small opening 20 for ejecting the steam generated in said body. The water which is fed to the inner end portion of the generator will be quickly turned to steam owing to the fact that the volume of said water is 15 limited and the body is arranged directly in the flame. The small elongated tube 21 prevents the water being supplied in too large quantities and the steam from forcing itself back into the water supply pipe 17. As fast 20 as the steam is generated, it is ejected through the opening 20 into the flame, thereby greatly improving combustion and blowing part of the heat units back to the opening 5 by reason of the fact that said generator and ejector points rearwardly. The 25 ejector in combination with the inclined plate 7 effectively distributes the heat units between the openings 4 and 5, and make it possible for a single burner to heat two cooking 30 vessels or other articles in addition to furnishing hot water by reason of the provision of the chamber 9 in the top plate and the coil 10 in the flame.

Having thus described my invention what 35 I claim as new and desire to secure by Letters Patent is:

1. In an attachment for stoves, the combination with a flue box having an opening in its bottom to fit over a burner of the stove, 40 and two openings in its top, one of said top openings being out of vertical alinement with the bottom opening, of a steam generator and ejector arranged above the bottom opening in the box and adapted to discharge 45 steam in the direction of the top opening which is out of line with the bottom opening.

2. In an attachment for stoves, the combination with a flue box having an opening in 50 its bottom to fit over a burner of the stove, and two openings in its top, one of said top openings being out of vertical alinement with the bottom opening, of a steam generator and ejector arranged above the bottom 55 opening in the box and adapted to discharge steam in the direction of the top opening which is out of line with the bottom opening, and an inclined plate extending from adjacent the bottom opening to the farther 60 side of the last mentioned top opening.

3. In an attachment for stoves, the com-

bination with a flue box having an opening in its bottom to fit over a burner of the stove, and two openings in its top, one of 65 said top openings being out of vertical alinement with the bottom opening, of a steam generator and ejector arranged above the bottom opening in the box and adapted to discharge steam in the direction of the top opening which is out of line with the bottom 70 opening, said generator and ejector comprising a tubular body having a conical tip provided with an outlet passage, means for supplying water to said body, and a valve for controlling the quantity of water supplied. 75

4. In an attachment for stoves, the combination with a flue box having an opening in its bottom to fit over a burner of the stove, and two openings in its top, one of 80 said top openings being out of vertical alinement with the bottom opening, of a steam generator and ejector arranged above the bottom opening in the box and adapted to discharge steam in the direction of the top 85 opening which is out of line with the bottom opening, said generator and ejector comprising a tubular body having a conical tip provided with an outlet passage, means for supplying water to said body, a valve 90 for controlling the quantity of water supplied, and a long tube having a small bore and extending from the valve a considerable distance into the body for the purpose specified. 95

5. In an attachment for stoves, the combination with a flue box having an opening in its bottom to fit over a burner of the stove, of a steam generator and ejector arranged over the said opening for ejecting 100 steam into the flame from the burner.

6. In an attachment for stoves, the combination with a flue box having an opening in its bottom to fit over a burner of the stove, of a coil of pipe arranged directly 105 over said opening, a steam generator and ejector also arranged over said opening, and means for circulating water through the coil and supplying water to the steam generator and ejector. 110

7. In an attachment for stoves, the combination with a flue box having two openings in its bottom to fit over two burners of the stove, and four openings in its top, two of 115 said top openings being out of vertical alinement with the openings in the bottom, of a partition dividing the box into two compartments each having one bottom opening, and two top openings, one of said top openings being out of line with said bottom opening. 120

JOHN A. BERRYMAN.
